UNITED STATES PATENT OFFICE.

GEORGE W. HAPPLE AND HUGO MAY, OF FORT WASHINGTON, MARYLAND,

FOUNTAIN-BRUSH.

1,049,863.

Specification of Letters Patent.

Patented Jan. 11, 1918.

Application filed February 6, 1912. Serial No. 675,710.

To all whom it may concern:

Be it known that we, GEORGE W. HAPPLE and HUGO MAY, citizens of the United States, residing at Fort Washington, in the county of Prince Georges and State of Maryland, have invented new and useful Improvements in Fountain-Brushes, of which the following is a specification.

Our invention relates to fountain brushes intended to be used for blacking shoes, or the like, the main object being the provision of a housing for the material container adapted to serve as a handle for the brush and so constructed as to permit easy access to the container for the purpose of operation or renewal of the same.

An object is the provision of a cap for the brush head carrying means for maintaining the bristles in soft pliable condition and further means for closing the feed duct when the brush is not in use.

A further object of the invention is the provision of means carried by the brush head by which the bristles may be compressed to permit ready insertion of the same into the cap without injuring the bristles.

Further objects of the invention will appear as the following specific description is read in connection with the accompanying drawings which form a part of the application, and in which:

Figure 1 is a side elevation of the device showing the cap removed and the movable portion of the handle in extended position; Fig. 2 is a transverse sectional view on line 3—3 of Fig. 1; Fig. 3 is a longitudinal sectional view of the device showing the cap in applied position; Fig. 4 is a bottom plan view of the same; Fig. 5 is a perspective view of the movable portion of the handle; and Fig. 6 is a transverse sectional view taken on line 6—6 of Fig. 3.

Referring now to the drawings, the numeral 1 designates a brush head which comprises a hollow body 2, preferably constructed of metal, and having its bottom open so as to receive the holder 3 for bristles 3a. Integrally formed with the head 1 is a rearwardly extending fixed portion 4 of the handle which is semi-cylindrical in shape and hollow so as to receive the collapsible material container 5. A feed duct 6 leads from an opening 7 in the rear wall 8 of the brush head through an opening 9 in the

bristle holder 3 to a discharge point below the holder 3. The lower edges of the fixed handle portion 4 are bent inwardly and upwardly to form flanges 4' which engage the flanges 4" formed by the outwardly and downwardly bent upper edges of a movable handle portion 10, as clearly shown in Fig. 2. This is to permit slidable movement of the portion 10 to unmask the collapsible container 5 which is threaded into the duct opening 7. The discharge end of the feed duct is flared outwardly and bears on a seat 11 for the closure 12 carried by the cap 13 when the cap is in applied position. Within the cap and surrounding the closure 12 is an absorbent pad 14 adapted to hold a suitable moistening liquid which will maintain the bristles in soft pliable condition while the brush is not in use. A bridle ring 15 encircles the bristles and has the extremities of its upwardly extending arms 17 and 18 indent to form stops 18 and 19 respectively which engage the guide brackets 20 and 21 to prevent undue downward motion of the bridle. Application of the cap 13 is facilitated by the use of this bridle which, when in lowered position, compresses the bristles so that they may be readily inserted in the cap. The head 1 is provided adjacent its lower edge with pins 22 which are received by the angular slots 23 in the cap so as to lock the cap in position upon slight rotation of the same.

The movable handle portion 10 is provided with an internal guide bracket 24 in which is slidably mounted the shank of a wrench 26, the inner end of the shank 25 being upturned to form a stop 27. This stop 27 is adapted to engage the inner edge of the guide bracket 24 and prevent excessive outward movement of the wrench through the opening 28 provided in the end of the movable portion 10. When the movable portion 10 is removed from its sliding engagement with the fixed portion 4, the wrench 26 may be projected through the opening 28 and used to screw the container 5 into position by applying the wrench to its angular neck 29.

When it is desired to use the brush, the cap 13 is removed and the bridle 15 pushed up into inoperative position. Then the movable portion 10 is slid outwardly to expose a sufficient length of the collapsible container 5, which is then compressed by the

fingers to force the semi-fluid material therein through the feed duct to the bristles 3^a.

Having thus described our invention what we claim as new is:—

1. A brush of the class described comprising a brush head, a fixed handle portion formed on said head, a movable handle portion slidably secured to said fixed portion, 10 a flexible container removably secured within the receptacle formed by said handle portions and extending longitudinally therein, and means for conducting semi-fluid material from said container to the bristles of the brush.
- 15 2. A brush of the class described comprising a brush head, a collapsible container

detachably secured to said head, means for conducting a semi-fluid material from said container to the bristles of the brush, a fixed 20 handle portion formed on said head and adapted to house partially the said container and a movable handle portion slidably associated with said fixed portion and adapted to house the remainder of the container.

In testimony whereof we affix our signatures in presence of two witnesses.

GEORGE W. HAPPLE.
HUGO MAY.
